LAWN EDGER BLADE

Ohmer L. Knapp, Kettering, Ohio, assignor to E-Z Products, Inc., Dayton, Ohio, a corporation of Ohio

Filed Apr. 26, 1965, Ser. No. 84,962

Term of patent 14 years

(Cl. D40—1)

FIG-1

FIG-3

FIG-2

FIG-4

FIG-5

FIG-6

FIG-7

FIG-8

FIGURE 1 is a perspective view of a lawn edger blade showing my new design; the broken lines are shown for illustrative purposes only.

FIGURE 2 is a perspective view taken from the opposite side of FIGURE 1.

FIGURE 3 is an elevational view of the blade member as seen in FIGURE 2 in an alternate position.

FIGURE 4 is an elevational view of the blade member as seen in FIGURE 1 in an alternate position.

FIGURE 5 is a top plan view of the blade member as seen in FIGURE 3.

FIGURE 6 is an end elevational view taken from the left of FIGURE 3.

FIGURE 7 is an end elevational view taken from the left of FIGURE 4.

FIGURE 8 is a bottom plan view of the blade as seen in FIGURE 4.

I claim:

The ornamental design for lawn edger blade, substantially as shown and described.
